GAUZE WIDTH CONTROL

Marshall M. Payne, Kannapolis, N. C., assignor to
Cannon Mills Company, Kannapolis, N. C.

Application June 28, 1940, Serial No. 343,039

1 Claim. (Cl. 139—195)

This invention relates to a control whereby the width of gauze being woven on a loom is made substantially uniform.

It is an object of the invention to provide means which will assure substantially uniform width while at the same time the tension is removed from the edges of the gauze during weaving.

Generally, as the amount of filler on the bobbin diminishes there is an increase in the tension of the filler which in turn causes a variation in the width of the gauze which may amount to about one-half an inch.

It is a further object of the invention to provide means which will counteract such tension variations which are due to variations in the amount of filler on the bobbin.

The uniformity of the width in gauze cloth is exceedingly important because during the tentering process unless the width is uniform there are large quantities of gauze which are damaged and rendered unfit for use. It is an object of the invention, therefore, to provide means which will assure absolute uniformity in the width of the gauze.

25 A still further object of the invention is to provide means which will eliminate any strain on the selvage thereby eliminating "hook" selvages or kinks adjacent the selvages.

Furthermore, in certain processes the selvages are later removed and if there are "hook" selvages or kinks such will cause ragged and uneven edges which would be very objectionable and would cause a further loss of material. It is an object of the invention to provide means which will 35 eliminate these disadvantages.

A further object of the invention is to provide means associated with the reed cap and the temples which will cooperate with the selvages to secure the objects mentioned above.

40 With the above and other objects in view, which will appear from the detailed description below, the invention is shown in the drawing in which:

Fig. 1 is a side view of a portion of a loom showing the reed cap, reed, lay and a portion of one 45 temple showing the invention as applied to the temple and the reed cap and illustrating in dotted lines the position occupied by the gauze width control when the lay is in its forward position.

Fig. 2 is a plan view of the parts shown in 50 Fig. 1, and

Fig. 3 is a partial cross-sectional view illustrating the manner in which the gauze width control is mounted on its supporting base carried on the top cap of the temple.

55 Referring to the drawing, in which similar

reference characters indicate like parts in the various views, the lay of the loom is shown at 5, the reed at 6, the reed cap at 7 and the warp shed at 8. The temple stem 9 is resiliently mounted in a temple housing (not shown) in the usual way. As is known, a temple is mounted on the frame at each side thereof. The top cap 10 is secured to the temple stem 9 by the top cap screw 11 and the top cap screw 11 is utilized in order to secure the gauze width control constituting the present invention, to the temple.

The base plate upon which the control is mounted is indicated at 12 and comprises a top horizontal portion 13, a side portion 14 extending downwardly at right angles from the top portion and a laterally extending flange portion 15 which is bent at right angles to the side portion 14.

A bearing 16 is secured to the side portion 14 of the base plate in any desired manner, preferably by threading, as shown at 17, and mounted on this bearing 16 is an actuating lever 18 of L-shape. The upper portion of the upwardly directed stem 19 of the lever 18 is formed preferably of fiber as shown at 20 in order 25 to eliminate excessive wear thereon. The fiber end 20 is secured to the lever by means of a bolt 21.

The actuating lever 18 is also provided with a substantial trunnion 22 positioned upon the bearing 16 and a nut 23 threaded upon the outer threaded end of the bearing 16 maintains the trunnion 22 and the actuating lever 18 in position on the bearing. A set screw 24 fixes the position of the nut 23 with relation to the bearing 16. 35

Encircling the trunnion 22 is a coil spring 25 having one end 26 positioned in a groove provided in the nut 23 and the other end 27 bearing against the top surface of the horizontally disposed stem of the actuating lever 18 so as to urge normally 40 the lever 18 against the lateral flange 15 of the base plate, as shown in full lines in Fig. 1.

A projecting member 28, preferably integral with the actuating lever 18 extends at right angles inwardly from the stem 19 of the actuating lever and is disposed on the side opposite to that upon which the trunnion 22 is located. The projecting member has fixed thereon at its inward free end the filler control 29 which is of 45 the shape shown particularly in Fig. 1. The filler control is adjustably mounted in the projecting member and is fixed in position by means of the set screw 30. The member 28 extends slightly above and parallel to the top cap of the 50 55

temple and when the actuating lever 18 is in the full line position of Fig. 1, the pointed end of the filler control 29 extends into the selvage of the gauze and supports the filler as the shuttle 5 passes through the shed.

Upon the reed cap 7 there is secured by the screws 31, a bracket 32 having spaced forwardly extending arms 33 in which the fiber roller 34 is mounted by means of the bearing shaft 35. 10 The operation of the gauze width control takes place as follows: Upon the forward movement of the lay 5 and the reed cap 7, the fiber roller 34 contacts the fiber end 20 of the actuating lever and pivots the lever to the dotted line position 15 shown in Fig. 1 against the action of the spring 25 on its bearing 16. This pivoting of the actuating lever also withdraws the pointed end of the filler control 29 from the selvage and permits the reed 6 to beat up the filler. Upon the backward movement of the lay with the reed, the spring 25 immediately returns the actuating lever 18 to the full line position of Figs. 1 and 2, so that the pointed end is in position to sustain the tension of the filler upon the next throw of 20 the shuttle. It will be noted that the filler control 29, when in the full line position of Fig. 1, comes to rest at a slight distance from the top cap of the temple and that in the return of the actuating lever the flange 15 of the 25 base plate 12 takes the blow. The filler control 29 is made adjustable in the projecting member 28 in order that it may be compensated for any wear in the temple or associated parts. The trunnion 22 is made of considerable width in 30

order to provide room for a relatively large spring 25 which is necessary in order to stand up under the relatively heavy work since the actuating lever will be operated normally about 180 times a minute. It has been found that fiber is more 5 satisfactory than metal in the operating roller 34 and the contact portion 20 of the actuating lever 18 although, of course, any desired material may be used in these locations.

As a rule, a plurality of slots may be provided 10 in the nut 23 for the accommodation of the end 26 of the spring 25 so that a finer adjustment of the tension of such spring may be obtained.

With the exception of the relatively short time of the beat up, both filler control members 29 15 at each side of the gauze are in position so as to support the tension of the filler and remove such tension from the selvage ends.

I claim:

A gauze width control for looms comprising a 20 base plate having a flange mounted upon the temple of the loom, a bearing secured to said base plate, an actuating lever, a trunnion upon said actuating lever engaging said bearing, a coil spring encircling said trunnion and normally 25 urging said actuating lever in contact with said flange, an extension upon said lever extending above and parallel to the top cap of said temple, a filler control adjustably mounted in said extension and a roller mounted upon the reed cap 30 of the loom adapted to engage said actuating lever to pivot the same and remove during the beat up said filler control from the cloth.

MARSHALL M. PAYNE.
